UNITED STATES PATENT OFFICE.

JOSEPH M. DENNING, OF DENVER, COLORADO.

FLOW-LIFT.

1,095,824.

Specification of Letters Patent.

Patented May 5, 1914.

Application filed October 3, 1912. Serial No. 723,801.

To all whom it may concern:

Be it known that I, JOSEPH M. DENNING, a citizen of the United States, residing at Denver, in the county of Denver and State of Colorado, have invented certain new and useful Improvements in Plow-Lifts, of which the following is a specification.

The present invention relates to a means for raising the plow bodies out of plowing 10 position and lowering the same into plowing position.

The objects of the present invention are to provide a single crank for actuating said plow lift; to so arrange the parts as to have 15 the plow enter the ground point down; to throw the point of connection between the crank and the parts connecting the crank with the plow body, past the center of movement of the crank, when the crank is fully 20 thrown to raised position; whereby the plow is locked in raised position; to provide a lever attached to the front end of the plow beam, to provide a shiftable fulcrum for this lever; and to provide a connection between 25 the lever and the crank and to provide means for adjusting this connection.

The invention further consists in the features of construction and combination of parts hereinafter described and claimed.

30 In the drawings, Figure 1 is a side elevation of a traction plow equipped with the mechanism of the present invention and with the engine or propeller removed; Fig. 2 a plan view of the part shown in Fig. 1; Fig. 3 a 35 detail of the plow lifting mechanism showing the plow in lowered position; Fig. 4 a view similar to Fig. 3 showing the plow raised; Fig. 5 a section on line 5—5 of Fig. 2, looking in the direction of the arrows; and 40 Fig. 6 a detail of the mechanism for leveling the frame.

The plow lift for illustrative purposes only is shown with a traction plow comprising side rails 7 and 8 joined together by a 45 front rail 9, a rear rail 10, and lying between the side rails and extending from the front rail to the rear rail is an intermediate rail 11, all of the rails being preferably of tubular formation which is of a nature to give 50 strength and durability to the frame-work without making the weight of the implement of undue proportions. Journaled upon the framework is a traction wheel 12 of suitable size and formation which is driven by a 55 motor, not shown, through the instrumentalities of suitable gearing 13.

Attached to the side rail 8, as best shown in Figs. 1 and 2, is a frame 14, which constitutes a carrying frame for an auxiliary wheel 15 lying approximately opposite the traction wheel. This auxiliary wheel serves as an added bearing for the rear end of the frame, so that when the device is working upon a hillside, the tendency of the rear end to tip will be overcome. The auxiliary 60 wheel is raised and lowered through the medium of a lever and segment mechanism 16, to the lever of which is connected a crank arm 17 which in turn is joined to a link or bar 18, connected at its rear end to the upper end of the frame 14. The connection between the link and frame is of the slot and pin variety, so that a certain amount of play is permitted between these two parts, and bearing against the link and the 65 upper end of the frame 14 is a spring 19 which tends to resist relative movement between the link and frame, and forms in effect a resilient connection between the frame and link. Should the wheel 15 be lifted, 70 the frame 14 would swing around its pivotal center, and the upper end would be forced against the spring 19, and owing to the slot and pin connection between the frame and link or bar the movement of the 75 frame would not disturb the position of the link, and hence the movement due to the rising of the auxiliary wheel would not be communicated to the supporting frame of the machine. Should the front wheels be 80 lifted from the ground by striking an obstacle the auxiliary wheel would not be affected thereby and would provide an added support so that the frame would not tip over. Should it be desired, however, to adjust the 85 height of the wheel 15, the lever, after a predetermined movement, would sufficiently compress the spring 19, so as to force the frame 14 and the wheel 15 downward in accordance with the rearward movement of the link 18, and if a raising of the wheel 90 95 15 were desired the lever, when moved in the opposite direction, would pull the link forward, and inasmuch as the pin is normally resting against the rear end of the 100 slot said forward movement would pull the frame 14 upward and raise the wheel 15. These movements, of course, if desired, could be utilized for leveling the rear end of the 105 frame since pressure when brought to bear 110 upon the wheel 15 when it was resting upon the ground would not disturb the position

of the wheel but would effect a tilting and leveling of the frame. This fact is well known to those acquainted with the plow art.

5 The implement is provided at the front end thereof with suitable steering wheels 20, each of which, in the construction shown as best illustrated in Fig. 5, is provided with a trunnion which terminates at its inner end 10 in a block or head 21, through which passes a vertically extending pivot pin 22, which also passes through ears 23 secured to the outer ends of the front axle 24, each of the steering wheels, as shown, being provided 15 with a circumferential rib or flange 25 to better insure its grip upon the ground. The axle 24 has secured thereto an upwardly extending lug 26 pivotally secured to a lug 27 depending from the front rail 9. This 20 pivotal connection permits of an up and down tilting of the axle in accordance with the movement of the wheel over the ground, and this pivot ~~further~~ provides the center of movement when an adjustment or leveling 25 of the frame is desired. The mechanism shown for effecting this adjustment consists of a link 28 secured to an ear 29 attached to a portion of the axle 24. The link in turn is pivotally connected to a pivoted 30 arm 30 having pivotally attached to its upper end a sleeve 31 provided with an interior thread, and extending through this sleeve 31 is a threaded stem 32 having a bearing in a sleeve 33 secured to a suitable support 34 35 attached to the side rail 7. The stem 32 is provided with a suitable handle 35 for rotating the same. The action of this mechanism will be obvious from the description: Rotation of the handle 35 in the direction 40 desired rotates the stem 32, moves the sleeve 31 along said stem, moves the crank arm 30 up or down about its center, raises or lowers the link 28 and effects the proper leveling of the frame, by reason of the fact that the 45 wheels 25 are resting upon the ground and will not be affected by the movements of the leveling mechanism. Of course, should one or the other of the wheels be upon a higher plane the lowering of one of the wheels 50 would take place when the rod 32 was properly turned.

The means illustrated for effecting a steering of the wheels 25 consists of a steering rod 36 provided with the usual hand-wheel 55 and terminating in its lower end in a worm surface 37, about which is wrapped a cable 38 connected to each of the blocks 21 of the trunnions of the wheel.

It is, of course, necessary to provide some 60 suitable means for raising and lowering the plow body to raise the plow clear from the ground when the implement is transported from place to place. After the plow has been lifted from the ground and is again 65 lowered into plowing position, it is highly

desirable that the front or point of plow strike the ground first, as in this position, it will more easily be dragged into proper plowing position by the forward movement of the implement. The mechanism shown 70 for effecting the raising and lowering of the plow consists of a crank 39 journaled in suitable bearings 40 attached to the rails 7 and 11. The crank is actuated by a lever 41 which is locked in position to hold the plow 75 raised through the instrumentalities of a detent adapted to engage with a tooth of a segment 42. Attached to the rear portion of the crank 39 is a link 44, which is secured by suitable means to the rear portion of the 80 plow 45, and attached to an arm 46 of the crank at a point intermediate the center of movement of the crank and the arm 43 thereof is a clip or ear 47, to the upper end of which is pivotally secured one end of a 85 link or bar 48. The other end of the link or bar is secured to the upper portion of a plate 49 which in fact is a bell crank lever; this lever is pivoted at 50 to a member 50^a which member is slidably mounted on a rod 90 53. The member 50^a furnishes what may be termed a shiftable fulcrum for the lever 49. The rod 53 is attached at one end to a member 50^b, which member is pivotally secured to a stem 50^c, which stem in turn is fixedly 95 attached to a plate 51 secured to the front rail 9 of the supporting frame. Pivoted attached to the lower portion of said plate or lever 49 is the front end of the plow beam 52, and the rod 53 is pivotally connected at its other end to said plow beam. The action of this portion of the device will 100 probably be best understood by referring to Figs. 3 and 4, the normal position being shown in Fig. 3, and as will be there seen, 105 the crank 39 is normally lying in a substantially horizontal plane. As the lever 41 is turned to swing the crank upward the link 44 will be swung upward carrying with it 110 the rear end of the plow, and the clip 47 will be pushed upward and forward forcing the link 48 forward, swinging the plate or crank 49 upward, and carrying the forward end of the plow beam 52 upward. Owing to 115 the fact that the clip 47 is located closer to the center of movement of the crank than the link 44, said link will, upon initial movement of the crank, travel a greater distance than the clip 47, and at the commencement 120 of the plow lifting operation the rear end of the plow will be carried up faster than the front end. When, however, the link 47 has crossed the center of movement of the crank 39, upward movement of the link 44 and the rear end of the plow will cease and 125 the link 44 will begin to descend and lower the rear end. This will occur during the latter portion of the movement of the crank. The clip 47, however, will continue to force 130 forward the link 48 until the crank has

made a complete semicircle. In the construction shown, the limit of movement of the crank is reached a relatively short time after the link 44 has reached its highest point, but the movement after the link has passed the center is sufficient to allow a continued raising of the front end of the plow beam, while the rear of the plow is being lowered, so that when the parts finally reach the final position, the plow is in a level or substantially level position. When the descent of the plow takes place, there will be no movement downward of the rear end until the crank 44 has fallen back past the axial center of the crank 39, and hence on the initial return movement of the crank, the rear end will not descend, but will instead rise. The plate 49, however, will be pulled backward at the commencement of the movement of the crank, and, therefore, the front end of the plow beam will be lowered at the commencement of said movement; thus when the rear end starts to be lowered, the plow will be at an angle so that the front end is pointing toward the ground, and the plow will enter the ground in this position. Then, as the machine is propelled forward, the drag of the plow will pull the rear end downward and into plowing position. An adjustment of the length of the link 48 is provided by forming a plurality of holes 56 at the front end of said link, the shortening or lengthening of this link regulating the depth to which the plow enters the ground.

I claim:

1. In a plow, the combination of a supporting frame, a plow body, a crank on said frame, a member pivotally connected to the front end of the plow body, a connection between said member and crank, a movable rod, a slidable connection between said member and rod, a connection between the rear end of the plow body and the crank, the connection between the rear end of the plow body and the crank and the connection between the pivoted member and the crank being located at different points upon the crank with respect to the center of movement thereof, substantially as described.

2. In a plow, the combination of a supporting frame, a plow body, a crank on said frame, a member pivotally connected to the front end of the plow body, a connection between said member and crank, a movable rod, a slidable connection between said member and rod, a connection between the rear end of the plow body and the crank, the connection between the rear end of the plow body and the crank and the connection between the pivoted member and the crank being located at different points upon the crank with respect to the center of movement thereof, and means for adjusting the length of the connection between the crank

and pivoted member, substantially as described.

3. In a plow, the combination of a supporting frame, a plow body, a member pivotally connected to the front end of the plow body, a crank carried by the frame, a connection between said pivoted member and crank, a rod pivoted to the plow beam and to the forward end of the supporting frame, a slidable connection between said pivoted member and rod, a connection between the rear end of the plow body and the crank, said connection from the pivoted member and said connection from the rear end of the plow body being located at different points upon the crank with respect to the center of movement thereof, substantially as described.

4. In a plow, the combination of a supporting frame, a plow body, a member pivotally connected to the forward end of the plow beam, a swinging rod, a slidable connection between said pivoted member and rod, a crank mounted on said frame, a lug on the crank, a link pivotally connected at one end to said member and pivotally connected at the other end to said lug and a connection between said crank and the rear end of the plow body, substantially as described.

5. In a plow, the combination of a supporting frame, a plow body, a crank on said frame, a connection between said crank and the forward end of the plow body, a member directly connecting the crank and the rear end of the plow body, the point of connection between the crank and the forward end of the plow being located closer to the center of movement of the crank than the point of connection between the crank and the member connecting the crank with the rear end of the plow body and both points of connections swinging past the center of movement of the crank when the crank is fully swung, substantially as described.

6. In a plow, the combination of a supporting frame, a plow body, a crank on said frame, a connection between said crank and forward end of the plow, means for directly connecting the crank and the rear end of the plow, the point of connection between the crank and the forward end of the plow being located closer to the center of movement of the crank than the connection between the crank and the connecting means to the rear end of the plow, both of said points of connections swinging past the center of movement of the crank when the crank is fully swung and means for adjusting the length of the connection between the crank and the front end of the plow, substantially as described.

7. In a plow, the combination of a supporting frame, a plow body, a lever pivotally connected to the front end of the plow, a shiftable fulcrum for said lever, a crank, a

- connection between said lever and the crank and a connection between the rear end of the plow and the crank, substantially as described.
5. 8. In a plow, the combination of a supporting frame, a plow body, a lever pivotally connected to the front end of the plow, a shiftable fulcrum for said lever, a crank, a connection between the lever and crank, 10 a connection between the rear end of the plow and the crank and means for adjusting the length of the connection between the crank and the lever, substantially as described.
15. 9. In a plow, the combination of a sup-

porting frame, a plow body, a lever pivotally connected to the forward end of the plow beam, a shiftable fulcrum for said lever, a crank mounted on said frame, a lug on the crank, a link pivotally connected at one end to said lever and pivotally connected at the other end to said lug and a link connected directly at one end to said crank and at its other end directly to the rear end of the plow body, substantially as described. 20 25
